UNITED STATES PATENT OFFICE.

JOHN BOULTBEE BROOKS, OF BIRMINGHAM, ENGLAND.

CYCLE-SADDLE.

SPECIFICATION forming part of Letters Patent No. 484,290, dated October 11, 1892.

Application filed April 8, 1892. Serial No. 428,367. (No model.) Patented in England April 20, 1888, No. 5,868; April 13, 1891, No. 6,283; December 3, 1891, No. 21,109, and March 16, 1892, No. 5,180.

To all whom it may concern:

Be it known that I, JOHN BOULTBEE BROOKS, manufacturer, a subject of the Queen of Great Britain, residing at Great Charles Street, in the city of Birmingham, England, have invented certain new and useful Improvements in Cycle-Saddles, (for which invention Letters Patent have been granted to me in Great Britain, dated March 16, 1892, No. 5,180; December 3, 1891, No. 21,109; April 13, 1891, No. 6,283, and April 20, 1888, No. 5,868;) and I do hereby declare the following to be a full, clear, and exact description of the invention, reference being had to the accompanying drawings, which form part of this specification.

This invention relates to detail improvements in the framings and fittings of cycle-saddles.

20 Figure 1 of the accompanying drawings represents, partly in longitudinal vertical section and partly in elevation, a constant-tension hammock cycle-saddle constructed, arranged, and fitted according to my invention. 25 Fig. 2 is an under side plan of the framing of the same. Fig. 2^A is a section of the joint part of the upper end of the pillar or supplementary spring. Fig. 3 is a transverse section of the L-pin boss upon the dotted lines 30 A B, Fig. 1.

The same letters of reference indicate corresponding parts in Figs. 1 to 3.

a is the seat of the saddle, suspended or supported upon nearly-parallel and horizontally-directed framing-rod, which are marked at rear and front by letters c⁴ c⁶. These suspension or framing rods, which are in double order, as represented in plan, and running nearly parallel under the seat of the saddle, 35 have loop-coiled springs c⁵ disposed a little rear of the L-pin boss i, by means of which latter, as hereinafter described, the saddle is secured by a claw attachment to the L-pin h of a machine. The rear ends of the said rods 40 of the parts c⁴ are turned upward into hook-shaped brackets c', terminated by eye-loops c³, which take upon hanging pins o, depending from the back under framing of the saddle-seat. Above and below the said eye-loops c³ are rear cushioning expedients in the

form of india-rubber blocks m, and with the whole kept up to their positions and to their bearings by nuts o', taking upon the ends of hanging pins o. The front ends of the parts c⁶ of the framing-rod are turned into loop-coils c², with the terminations of the rods forming them bent slightly inward and upward into curved brackets c⁷, having a returned part or loop c⁸, which is embraced by the hook l³ of a hooked tension-pin l, passing through a plain hole k² of a hanging bracket k, and which tension-pin is adjusted by the rotation of a screw-nut k' taking on the end of the pin located at the back of the bracket k.

Located rearward of the bracket-arms c⁷ and loop c² and disposed between the under side of the bracket k, and the fore part of the frame-rod c⁶ is a vertically-directed pillar-coiled spring p, secured at its lower end to a bridge-bracket c⁹ by a pin c¹⁰, and at its upper end jointly connected to the bracket k by a depending part k³, (see Fig. 2^A), taking into a hole p³ of a seating p², surmounting the said spring p. Hence the jointed connection. Before the connection of the loop-coiled bracket c⁷ c⁸ is made with the hook l³ the said bracket or bracket-arms come considerably forward of their acting position, so that on making the connection the coils of the loops c² are slightly contracted or wound up by bringing the said bracket or bracket-arms into an upright position, as shown. Hence a constant tensioning.

The supplementary upright pillar-coiled spring p supports the fore part of the saddle, 85 and the seat thereby is prevented from sagging, as is common with hammock-saddles as ordinarily suspended.

The L-pin boss i, which is segmental in construction, affixes both the saddle-iron or L-pin h and also itself to the base framing-rod by the screwing home of a single screw-pin, as hereinafter described. Thus the L-pin boss i consists of a middle part i², with neck i³, wherethrough a clamping screw-pin i⁴ upwardly passes, with its extreme end impinging upon the saddle-iron or L-pin h. The upper terminal ends of the said sectional middle part have inverted claws i⁵, with semicircular recesses i⁶, which embrace the base 100

framing-rod c^8 . The middle part consists of a section having opposite under bearing sides i^7 , with gaps i^8 , middle solid part i^9 , and saddle-iron or L-pin bearing i^{10} . The placing of the said embracing parts i^5 i^7 around the frame-rod c^8 and the passing of the horizontal limb of the saddle-iron or L-pin h through the recess i^{11} , formed between the sections, as aforesaid, the screwing home of the screw or set pin i^4 affixes rigidly the said saddle to the L-pin or saddle-iron.

It is understood that the framing-rod and springs are in double order.

Fig. 4 represents a hammock-saddle with rear cushioning expedients, having a plain or dissimilar-shaped framing. Fig. 5 is an inverted plan of the fore part of the same. a is the seat of the saddle. m are rear end cushioning expedients; c^4 c^6 , framing-rod which are in double order; c^5 , a double loop-coil; i , L-pin boss; h , the L-pin. The rear looped ends c^3 of the framing-rod come between the threaded rubber blocks or cushioning expedients m , which are threaded upon screw-pins o , hanging from the under side of the after end of the saddle. The fore part of the said framing-rod is shaped alike unto a sleigh-runner c^7 , and has a looped end c^8 , which takes over a hooked end l^8 , and a tension-screw l , which takes through the plain hole of a hanging bracket k and is adjusted by a screw-nut k' .

Fig. 6 represents a modified form of a saddle provided with rubber-cushioned rear end connections. a is the seat of the saddle; b , the frame-rod; m , rubber pads or rear cushioned end connections or cushioning expedients, with washers m^2 upon either side of them. n is an H-shaped bracket with branch end loops n' n^2 , the upper ones n' of which come between the pads m of the upper series, and with the lower one n^2 coming upon the upper pad m of the lower series, while the end loop c^8 of the base framing-rod c^4 c^8 , with a loop-coil c^5 , come between both of the rubber pads m of the lower series, and which series are in double order, as shown in back elevation at Fig. 7. i is the L-pin boss, and h the L-pin, c^2 the front loop-coiled springs, and c^7 the bracket end.

Having described my invention, what I claim as new is—

1. In a cycle-saddle, suspending or supporting the seat of the same from frame-rod c^4 c^6 , having loops c^2 c^5 and bracket c^7 , in combina-

tion with rubber cushioning-blocks m , as set forth.

2. In a cycle-saddle, combining with the rear end framing n of the same rubber blocks m , as set forth in Figs. 6 and 7. 60

3. In a hammock cycle-saddle, the combination, with the frame-rod c^4 c^6 and bracket or fore part c^7 , of a pillar-coiled spring p , located between the front under side of the seat of the saddle and the base framing-rod rear of the said front or bracket part c^7 , as set forth. 65

4. In a hammock cycle-saddle, the combination, with the seat and framing-rod, of a supplemental erect pillar-coiled spring p , disposed rear of the front of the said framing-rod, as set forth. 70

5. In a hammock cycle-saddle, the combination, with the seat of the same, of a tension-pin l , having hooked end l^8 , as set forth.

6. In a hammock cycle-saddle, the combination, with the framing-rod c^4 c^6 , having expedients m , body-coils c^5 , and looped front looped ends c^3 , fitted with rubber cushioning coils c^2 , having bracket-arms c^7 c^8 , connected by a tension-screw pin l^8 , carried by a bracket k k^2 and secured by a nut k' , of a supplemental pillar-coiled spring p , located between the bracket k of the frame-rod c^6 and connected at top by a joint k^3 p^2 p^3 and at bottom supported by and attached to a bridge-bracket c^9 , as set forth. 85

7. In a hammock cycle-saddle, the combination, with the supplemental spring p , of a spring bracket arm or arms c^7 , situated forward of the said spring and adapted to pull 90 or keep on stretch the seat of the saddle by its outward tension, as set forth.

8. In saddle-iron or L-pin bosses, the combination, with rod-framings and L-pins, of clawed and gapped sections, with set-screw 95 passing up a neck of the middle one of them, as set forth, whereby the screwing up of the said set-screw affixes the boss to the framing-rod and the saddle to the L-pin.

9. In saddle-iron or L-pin bosses, the combination, with rod-framings and L-pins, of clawed and gapped sections, as set forth. 90

In testimony that I claim the foregoing I have hereunto set my hand this 26th day of March, 1892.

JOHN BOULTBEE BROOKS.
